FEEDING MECHANISM FOR SEWING MACHINES

Nicholaus Knaus, Newark, N. J., assignor to The Singer Manufacturing Company, Elizabeth, N. J., a corporation of New Jersey

Application September 19, 1933, Serial No. 690,061

4 Claims. (Cl. 112—209)

This invention relates to improvements in sewing machines, and more particularly to a feeding mechanism embodying two feed-dogs which are given differential movements relative to each other.

In the drawings:

Figure 1 is a view partly in plan and partly in section, showing a machine having my improved feed-adjusting mechanism embodied therein.

10 Figure 2 is a sectional view taken along the line 2—2 of Figure 1.

Figure 3 is a rear elevation of a portion of a sewing machine having my improved feed-adjusting mechanism embodied therein.

15 Figure 4 is a perspective view of the feed-adjusting mechanism.

My improved feed-adjusting mechanism is shown applied to an overseaming machine such as that disclosed in the patent to A. Grieb, No. 20 933,033, dated August 31, 1909, and in my co-pending application Serial No. 639,976, filed October 28, 1932. In the embodiment shown, 1 is the bed of the machine having suitable bearings in which are journaled a main-shaft 2, 25 and rearwardly extending bearing supports 3 formed with suitable bearing apertures to receive the feed-rock shaft 4.

Fixed upon the feed rock-shaft 4 is the feed-rocker 5 having two spaced lateral arms 6 and 30 7, each arm having an apertured end which receives a pivot-pin 8. The feed-rocker 5 receives an oscillatory movement from the main-shaft by means of a pitman 9 having one of its ends embracing an adjustable eccentric 10 on the main-shaft 2, and its other end connected by a pivot-pin 11 to the depending arm 12 which has its split-hub 13 secured to the feed-rocker 5.

Disposed intermediate the arms 6 and 7 of the feed-rocker and carried by the pivot-pin 8 is 40 the enlarged apertured end 14 of the auxiliary feed-bar 15 which carries on its forwardly projecting end 16 the auxiliary feed-dog 17. A main feed-bar 18 is slidably carried on the auxiliary feed-bar 15, the main feed-bar being provided 45 with a rib 19 which enters the channel 20 in the auxiliary feed-bar and a longitudinal aperture 21 which receives the stud 22 carried by the auxiliary feed-bar. The above described connection permits the main feed-bar to be reciprocated on the auxiliary feed-bar and independently thereof, but connected thereto, so as to be moved up and down therewith. The forward end of the main feed-bar carries a main feed-dog 23 which is located in rear of and substantially in 50 alignment with the auxiliary feed-dog 17.

The auxiliary feed-bar 15 overhangs the usual feed-lift eccentric 24 on the main-shaft and a short pitman 25 embracing the feed-lift eccentric is pivotally connected to the bar 15 by means of a pivot stud 26 carried by the pitman. 5 Through this connection with the main-shaft, the feed-bars receive their rising and falling movement. The above described differential feeding mechanism is substantially the same as that forming the subject of my copending application Serial No. 639,976, filed October 28, 1932, to which reference may be had for a more detailed description.

In order to vary the throw of the main feed-dog relative to the auxiliary feed-dog, I have 15 connected the main feed-bar to an adjustable sliding member 27 by means of a link 28. The adjustable sliding member is provided with a slot 29 and a rearwardly projecting hand piece 30. The walls of the slot 29 slidably engage a boss 31 20 carried by the arm 7 of the rocking frame 5 so that the pivotal connection between the main feed-bar and the rocking frame may be shifted relative to the axis of oscillation of the rocking frame to vary the throw of the main feed-bar. 25

To lock the adjustable member 27 in any desired position the rearwardly projecting hand-piece 30 has a locking-dog 32 pivoted thereto by means of the pivot-screw 33. The locking-dog 32 is formed with a toothed portion 34 which 30 co-acts with the toothed section 35 formed on the retaining plate 36 which is fixed by the screw 37 to the boss 31 and arm 7. A compression spring 38 reacts between the hand-piece 30 and the locking-dog 32 and tends to constantly urge the 35 locking-dog into engagement with the toothed section 35. It will be observed from the foregoing that the hand-piece 30 and locking-dog 32 are located in rear of the machine so that they 40 may be readily grasped by the operator, and the sliding member 27 shifted to any desired position. This construction is compact, rugged, and easily 45 and quickly operated. It will also be observed that the plate 36 serves a double purpose, first as a retaining plate for preventing the sliding member 27 from moving longitudinally of the rocking frame, and second, as locking member 45 for the locking-dog 32.

It is often desirable to shift the pivotal connection between the rocking-frame and the main feed-bar between predetermined positions in order to vary the feeding action of the feed-dogs. To this end I have threaded into the upper end of the sliding member 27 a set-screw 39 and provided a locking-nut 40 to lock the screw 39 50 55

against turning once it has been set at the desired position. A stop-plate 41 is adjustably secured to the arm 7 by means of a screw 42 which extends through the slot 43 in the plate 41 and is threaded into the arm 7 of the rocking frame 5. From the foregoing it will be obvious that the screw 39 may be adjusted to limit the downward movement of the sliding member 27 and that the plate 41 may be adjusted to a position which will limit the upward movement of the member 27.

Having thus set forth the nature of the invention, what I claim herein is:—

1. In a differential feeding mechanism for sewing machines, a feed-rocker including an arm having a boss projecting from one side thereof, said boss presenting surfaces which are spaced from one another, an adjustable member formed with a slot the walls of which slidably engage said surfaces, said adjustable member having a rearwardly projecting hand-piece, a spring-biased locking member carried by said hand-piece, a locking element fixed to said feed-rocker in cooperative relation with said locking member, main and auxiliary feed-bars connected to be operated by said feed-rocker and said adjustable member, and means for raising and lowering said feed-bars.
2. In a differential feeding mechanism for sewing machines, a feed-rocker including an arm having a boss projecting from one side thereof, said boss presenting surfaces which are spaced from one another, a slidable member formed with a slot the walls of which slidably engage said surfaces, said slidable member having a projecting hand-piece, a locking member carried by said hand-piece, a locking element with which said locking member cooperates to lock the slidable member in its adjusted position, an adjustable

stop to limit the upward movement of said slidable member, a second adjustable stop to limit the downward movement of said slidable member, main and auxiliary feed-bars connected to be operated by said feed-rocker and said slidable member, and means for raising and lowering said feed-bars.

3. A feeding mechanism for sewing machines including in combination, a feed-rocker having spaced arms, an auxiliary feed-bar pivoted between said arms, means for raising and lowering said feed-bar, a main feed-bar slidably carried on said auxiliary feed-bar, a boss carried by one of said arms, an adjustable member formed with a slot the walls of which slidably engage said boss, said sliding member having a rearwardly projecting hand-piece, a locking member carried by said hand-piece, a plate with which said locking member cooperates to lock the adjustable member in its desired position, and a link pivotally connecting said main feed-bar with said adjustable member.

4. In a differential feeding mechanism for sewing machines, a feed-rocker including an arm having a boss projecting from one side thereof, an adjustable member formed with a slot the walls of which slidably engage said boss, a plate secured to said boss for retaining said adjustable member on said boss, a rearwardly extending hand-piece on said adjustable member, a locking-dog pivotally secured to said hand-piece and cooperating with serrations on said plate for locking said adjustable member in its desired position, main and auxiliary feed-bars connected to be operated by said feed-rocker and said adjustable member, and means for raising and lowering said feed-bars.

NICHOLAUS KNAUS.
